UNITED STATES PATENT OFFICE.

CHARLES H. MEAD, OF KENT, OHIO, ASSIGNOR TO THE NATIONAL SAFE AND LOCK COMPANY, OF CLEVELAND, OHIO.

SAFE.

SPECIFICATION forming part of Letters Patent No. 558,088, dated April 14, 1896.

Application filed July 10, 1895. Serial No. 555,498. (No model.)

To all whom it may concern:

Be it known that I, CHARLES H. MEAD, a citizen of the United States, residing at Kent, in the county of Portage and State of Ohio, have invented a new and useful Improvement in Safes, of which the following is a specification.

My invention relates principally to safes in which the door is swung free of the safe by means of a crane-hinge or traverse hinge; and the object of my invention is to provide a means by which the door in opening and closing may be held in the proper position to be projected into the jamb of the safe.

15 The invention hereinafter described is designed especially for use with safes known as the "round-door" kind, but may be used to equal advantage with any safe in which the door is swung free of the safe by means of a 20 crane or traverse hinge.

My invention is illustrated in the accompanying drawings, in which—

Figure 1 represents the front of a round-door safe having a part of the hinge and outer side plate of the door broken away to show the fastening-bolt and its application to the door. Fig. 2 is a sectional view of the safe and door on line $x-x$ of Fig. 1, also showing the hinge and a top view of the fastening device. Fig. 3 is the same as Fig. 2, except that the door is shown open and engaged by the fastening device. Fig. 4 is a side view of the fastening device, having a part of the sleeve which holds the fastening bolt removed to show the fastening-bolt. Fig. 5 is an end view of the fastening device. Fig. 6 shows a modification of the form of the projecting block.

Like letters refer to like parts in the several views.

In the drawings, A represents the safe-door of a round-door safe. The door A is swung on hinges B B, which hinges are connected by a plate C. The door may be swung away 45 from the safe upon the hinges B B. The door is held between the hinges B B upon pins o o, upon which it may be turned, and is also adapted to revolve within the hinges.

The device for holding the door when opened 50 consists of a sliding bolt d, which moves in a

sleeve e, having a suitable opening to conform to the bolt. The bolt d is pressed forward by means of a spring f in the sleeve. Attached to the bolt d is a pin g, which moves with the bolt in a slot in the sleeve. 55 The pin g is also provided with a friction-wheel h, and between the wheel h and the spring-barrel is a sliding plate i, which moves with the bolt d and its pin g and wheel h and tends to hold the wheel and pin rigidly 60 and to cause the bolt to slide smoothly.

While the plate i is desirable to insure the smooth working of the bolt, it may be omitted, if desired.

The wheel h engages a projecting block k, 65 attached to the wall of the safe and having a single incline face k', as shown in Figs. 2 and 3, or having also a second incline face p, as shown in Fig. 6.

In the drawings the sleeve is provided with 70 a plate m, by means of which it is attached to the hinge-plate C. The manner of attaching the sleeve e to the hinge is, however, not material to my invention.

The operation of the fastening device is 75 apparent from the drawings.

When the door is closed, the bolt d is held away from the safe-door by the contact of the wheel h with the incline face of block k or k', as shown in Fig. 6. When the door is opened, 80 the outward movement of the door allows the wheel h (pressed forward by spring f bearing upon the bolt d) to pass down the incline face of the projecting block, and the bolt d engages an opening at n in the door and holds 85 the door in a suitable position to be closed. When the door is swung inwardly in closing, the contact of wheel h with incline face of the projecting block causes the withdrawal of bolt d from the door, and the door, when it 90 enters the opening in the safe, is free to be turned and closed, as desired.

If desired, the bolt may be pressed forward by the contact of wheel h with the incline face p of block k', as shown in Fig. 6, and I 95 do not limit my invention to the use of the spring f alone for pressing the bolt forward, as it is apparent that the incline face p may be substituted for the spring f or may be used in conjunction with the spring f.

If desired, the friction-wheel *h* may be omitted and the pin *g* made to engage directly the face or faces of the projecting block.

What I claim, and desire to secure by Letters Patent, is—

1. In a safe, in combination with the door and its hinge, a sliding bolt engaging the door, and held by a suitable sleeve attached to the hinge, and having pin *g* which engages the 10 incline face of a projecting block attached to the safe, substantially as shown and described.

2. In a safe, in combination with the door and its hinge, a sliding bolt engaging the door, and held by a sleeve attached to the hinge, 15 and being engaged by a spring *f*, the bolt also having pin *g* which engages the projecting block *k* substantially as and for the purposes shown and described.

3. In a safe, in combination with the door 20 and its hinge, a sliding bolt held by a suitable sleeve attached to the hinge and being engaged by the spring *f*, the bolt also having

pin *g* provided with friction-wheel *h* which engages the projecting block *k* attached to the safe, substantially as shown and described. 25

4. In a safe, in combination with the door and its hinge, the sliding bolt held in a suitable sleeve attached to the hinge and being engaged by spring *f*, the sliding plate *i* and the pin *g* attached to the bolt and engaging the projecting block *k*, substantially as and for the purposes specified. 30

5. In a safe, in combination with the door and hinge, the sliding bolt held in a suitable sleeve attached to the hinge and being engaged by a spring *f*, the sliding plate *i*, the pin *g* attached to the bolt and being provided with friction-wheel *h* which engages the projecting block *k*, substantially as shown and described. 35

CHARLES H. MEAD.
